FOUNTAIN COMB

Edward H. McCain, Raleigh, and Claude E. Neal,
Durham, N. C.

Application February 10, 1950, Serial No. 143,432

3 Claims. (Cl. 132—13)

1

This invention relates to improvements in combs, and more particularly to a comb of the fountain type.

A main object of the invention is to provide a novel and improved fountain comb which may be used for dispensing hair tonic, liquid hair lotion, or other hair treatment liquids, said comb being simple in construction, easy to operate, and being arranged to prevent waste of the hair treatment liquid carried therein.

A further object of the invention is to provide an improved fountain comb which is compact in size, light in weight, which involves only a few parts, which is easy to manipulate for opening and closing the valve elements thereof, and providing a device for applying a hair treatment liquid to the hair while the hair is being combed, the liquid being applied in an economical and efficient manner.

Further objects and advantages of the invention will become apparent from the following description and claims, and from the accompanying drawings, wherein:

Figure 1 is a side elevational view of an improved fountain comb constructed in accordance with the present invention;

Figure 2 is an end elevational view of the fountain comb of Figure 1;

Figure 3 is an enlarged, vertical, transverse, cross-sectional view taken on line 3—3 of Figure 1;

Figure 4 is a fragmentary cross-sectional view taken on line 4—4 of Figure 3;

Figure 5 is an enlarged, cross-sectional, detail view taken through the air vent control means included with the valve-operating means of the fountain comb of Figures 1 to 4;

Figure 6 is a fragmentary, cross-sectional, detail view showing in enlarged proportions one of the needle valve elements and the valve seat therefor, as employed in the fountain comb shown in Figures 1 to 4.

Referring to the drawings, 11 generally designates the body of the comb, said body comprising a longitudinally extending reservoir 12 having secured to its longitudinal lower margin the depending comb teeth indicated at 13 and 14. The teeth 13 are relatively closely spaced and are relatively small in cross-sectional area, whereas the teeth 14 are more widely spaced and are larger in size than the teeth 13. As shown in Figure 3 and in Figure 4, the bottom wall of the reservoir 12, shown at 15, is formed with spaced, vertical openings 16 which are located between adjacent teeth 14. Designated at 17 is a longi-

2

tudinally extending, vertical plate member carried inside the reservoir 12, said plate member 17 having secured to its lower margin respective needle members 18 which extend sealingly and slidably through sealing bushings 19 secured in the lower reservoir wall 15, said needle members engaging slidably in the vertical openings 16. Secured to the intermediate portion of the top edge of the plate member 17 is an upwardly extending, vertical tube 20 which extends slidably through a sealing bushing 21 secured in the top wall of the reservoir 12, as shown in Figure 4, a knob member 22 being secured to the top end of the tubular member 20. Tubular member 20 is formed with a pair of apertures 23 and 24, the aperture 23 being located at the lower portion of the tubular member, and the aperture 24 being located a substantial distance above the aperture 23. The spacing of the apertures 24 and 23 is such that when the knob member 22 is raised, as shown in Figure 5, to a position wherein the needle members 18 are raised above their bushings 19 sufficiently to allow liquid to flow past the needle valves and through the openings 16, the upper vent aperture 24 is raised above its sealing bushing 21, as shown in Figure 5, to allow air to enter the reservoir through the tubular member 20.

The plate member 17 is formed adjacent its respective ends with laterally projecting lugs 25 projecting on opposite sides of the plate member 17, respective pairs of resilient guide plates 26, 26 being secured within the reservoir at opposite sides of the plate member 17 adjacent the respective projections 25. The plate members 26, 26 are formed with upper notches 28, 28 and with lower notches 29, 29, the projections 25, 25 being received in the lower notches 29, 29 when the plate member 17 is in its lower, valve-closing position, and the projections 25, 25 being received in the upper notches 28, 28 when the plate member 17 has been raised to positions wherein the needle valves 18, 18 are in open relation with respect to their sealing bushings 19. The spacing between the shoulders 30, 30 between the notches 28 and 29 of the plate members 26 is just sufficient to allow passage therebetween of the projections 25, 25 when the plate member 17 is moved either from its upper to its lower position, or from its lower position to its upper position. Since the plate members 26, 26 are somewhat resilient, the projections 25, 25 may make a very close fit between the shoulders 30, 30, inasmuch as the shoulders 30, 30 will yield to permit passage therebetween of the projections 25, 25.

One end wall of the reservoir 12, shown at 31, is formed with a filling spout 32 provided with a threaded closure cap 33.

In using the device, the reservoir 12 is first filled with the desired hair treatment liquid, said reservoir having a capacity sufficient to receive enough liquid for use of the comb over an extended period of time. When it is desired to apply the liquid, the button 12 is pulled upwardly from the position of Figure 3 to the position of Figure 5, whereby the needle valve elements 18 are raised to positions wherein their tapered end portions clear the sealing bushings 19 sufficiently to allow the liquid to flow downwardly through the vertical openings 16. At the same time, the tubular member 20 has been raised to a position wherein air may enter the upper portion of the reservoir 12 through the upper apertures 24, the tubular member 20 and the lower apertures 23 in said tubular member. Under these conditions, the liquid may flow smoothly out through the bottom wall of the reservoir between the teeth 14 during the combing of the hair. The valve plate support member 17 is held in its raised position by the locking cooperation of the projections 25, 25 in the upper notches 28, 28 of the guide plates 26, 26.

To close off the outlet valves in the lower wall 15 of the reservoir, it is merely necessary to depress the button 22, moving the needle valve elements 18 downwardly into the sealing bushings 19 and into the openings 16, whereby said openings 16 are closed off, the valve plate support member 17 being held in valve-closing position by the locking cooperation of the projections 25, 25 in the lower notches 29, 29 of the guide plates 26, 26.

While a specific embodiment of a fountain comb device has been disclosed in the foregoing description, it will be understood that various modifications within the spirit of the invention may occur to those skilled in the art. Therefore, it is intended that no limitations be placed on the invention except as defined by the scope of the appended claims.

What is claimed is:

1. A fountain comb comprising a hollow body, comb teeth secured to the bottom wall of said body, said bottom wall being formed with vertical openings between certain of the comb teeth, a plate member slidably mounted for vertical movement in said body, depending needle valve members carried by said plate member and engaged in said openings, and a tubular member secured to the upper portion of said plate member and extending slidably through the top wall of the body, said tubular member being formed with spaced apertures, one of said apertures being positioned adjacent the upper portion of said plate member and the other of said apertures being positioned adjacent the inner surface of the top wall of said body, the spacing of said apertures being greater than the thickness of the top wall of said body, whereby sliding upward vertical movement of said plate member will cause the other of said apertures to be exteriorly of the outer surface of the top wall of said body.

2. A fountain comb comprising a hollow body, comb teeth secured to the bottom wall of said body, said bottom wall being formed with vertical openings between certain of the comb teeth, a plate member slidably mounted for vertical movement in said body, depending needle valve members carried by said plate member and engaged in said openings, a tubular member secured to the upper portion of said plate member and extending slidably through the top wall of the body, said tubular member being formed with spaced apertures, one of said apertures being positioned adjacent the upper portion of said plate member and the other of said apertures being positioned adjacent the inner surface of the top wall of said body, the spacing of said apertures being greater than the thickness of the top wall of said body, whereby sliding upward vertical movement of said plate member will cause the other of said apertures to be exteriorly of the outer surface of the top wall of said body, and interengaging locking means carried by the plate member and the body formed and arranged to releasably secure the plate member in any one of a plurality of positions in said body.

3. A fountain comb comprising a hollow body, comb teeth secured to the bottom wall of said body, said bottom wall being formed with vertical openings between certain of the comb teeth, a plate member, guide plates secured in said body on opposite sides of said plate member, said plate member being vertically slidably between said guide plates, depending needle valve members carried by said plate member and engaged in said openings, a tubular member secured to the upper portion of said plate member and extending slidably through the top wall of the body, said tubular member being formed with spaced apertures, one of said apertures being positioned adjacent the upper portion of said plate member and the other of said apertures being positioned adjacent the inner surface of the top wall of said body, the spacing of said apertures being greater than the thickness of the top wall of said body, whereby sliding upward vertical movement of said plate member will cause the other of said apertures to be exteriorly of the outer surface of the top wall of said body, and interengaging locking means carried by the plate member and the guide plates formed and arranged to releasably secure the plate member in any one of a plurality of vertically adjusted positions in said body.
